UNITED STATES PATENT OFFICE

2,555,153

HOLDER FOR ABRASIVE OR CLEANSING MATERIALS

Jack Rakoff and Ruth Rakoff, Brooklyn, N.Y.

Application May 15, 1947, Serial No. 748,180

5 Claims. (Cl. 15—209)

1

This invention relates to improvements in holders for materials used in cleaning, scouring, polishing, and the like, and will be found especially useful as a household appliance, although its use is obviously not confined thereto.

An object of the invention is to provide such a holder which will provide a handy gripping means for materials such as steel wool, fabric waste, rags, cloth, etc., so that they may be used while avoiding direct contact with the hands, thus avoiding the dangers of being cut by particles of steel wool or having the hands soiled from contact with fabric materials.

Another object of the invention is to provide a holder so designed that the hands are kept from contact with the object being scoured or cleaned.

Another object of the invention is to provide a holder having positive internal gripping means for the scouring or cleaning material, said gripping means being simple of construction and easy to engage with and disengage from the material to be used. A further advantage of said gripping means is that they form no outer projection apt to catch in the user's hands or clothes, or tending to interfere with the scouring or cleaning operation.

A further object of the invention is to provide a holder capable of gripping portions of bulk steel wool or the like, it not being necessary to have the scouring or cleaning material molded or preformed in any particular shape in order to be adaptable to the holder.

A further object of the invention is to provide a simple and durable holder which is cheap to construct, and which has a minimum of operational parts which could break or deteriorate.

Other objects of the invention will be understood from the description of the drawing which follows. In said drawing:

Fig. 1 is a side view, with broken away portions in section, showing one modification of the invention;

Fig. 2 is a sectional view taken on the lines 2—2 of Fig. 1, but with the abrasive or cleaning material shown in Fig. 1 omitted;

Fig. 3 is a side view, with broken away portions in section, showing the invention with modified material gripping means;

Fig. 4 is a sectional view showing another modification of the invention;

Fig. 5 is a sectional view showing a further modification of the invention; and

Fig. 6 is a perspective detail of the disc which forms part of the material gripping means of the modifications of Figs. 4 and 5.

In these figures the invention has been illustrated as having a body composed of plastic material, which material will be found to be well suited therefor; it is obvious however, that the

2

same may be constructed of wood, metal, or any other material adaptable to the purposes of the invention.

In Fig. 1, the body 10 is shown as formed of two interlocking sections 11 and 12 which form a rounded body surface and are joined as by a friction or snap joint 13. Snap joint 13 is a convenient means of closing the body 10; however, this particular means does not form an essential part of the invention, and other closing means of sufficient strength may be substituted, such as a screw-threaded joint.

Interiorly of the upper half 11 of body 10 is formed a projecting seat 14 over which the end 15 of spring 15 is coiled, thus positioning said spring in operative position. The lower end of spring 15 is formed in a flat loop 16, which loop is slightly larger than the lower opening of body 10, as may be best seen in Fig. 2.

The lower end of section 12 of the body 10 is tapered to form a circular opening, and projecting inwardly and upwardly of said opening are formed integrally with body 10 the substantially rigid material gripping teeth 17. These teeth are adapted to cooperate with the lower loop 16 of spring 15 to provide clamping means for the scouring or cleaning material to be placed in the holder.

In Fig. 1, such material, indicated at 18, is shown in operable position in the holder. To insert such material in the holder all that is necessary is to insert a portion thereof through the lower opening of holder 10, thus raising spring 15. The portions of the material entering the opening will thus be caught and held by the clamping and biting action of loop 16 and teeth 17. To remove the cleaning material 18, spring 15 may be raised as with the finger, and material 18 may then be disengaged from teeth 17; or, the holder 10 may be opened at joint 13 and spring 15 may be removed.

In the modification shown in Fig. 3, the holder 10 and the spring 15 are the same as previously described; however, in this modification there is added a seating disc 19 in which is seated the lower end of spring 15. Seating disc 19 provides a larger and flatter contact surface than does the end 16 of spring 15, and may be employed when it is desired to increase the gripping action against the teeth 17.

In the modification of Fig. 4, the holder 10 is again as previously described. In this modification a U-shaped spring 20 is employed in place of the coil spring 15 just described. Gripping contact with the material 18 is provided by disc 21 which is formed with a punched out loop 22 adapted to fit over and be carried on spring 20. The gripping action of this modification is provided by the thrust of spring 20 which presses the

material 18 between disc 21 and teeth 17. A perspective of disc 21 is shown in Fig. 6.

In the modification of Fig. 5, disc 21, as just described, cooperates in the same manner with teeth 17, but is activated by an S-shaped spring 23. A seat 24 is provided on the inner wall of holder 10 to hold in place the upper end of spring 23.

In the claims which follow the word "material" is used as a short definition of all cleaning, scouring, or polishing materials capable of being placed in and used with the holder constituting the invention, and includes the materials specifically suggested for use therewith in the above description.

Having thus described the invention, what is claimed is:

1. A material holder suitable for manual polishing, scouring, cleaning, or the like, comprising a hollow body having a relatively large convex upper rounded portion of dimensions providing a hand grip, said upper portion tapering into a lower relatively small material-gripping portion terminating in an open mouth; a plurality of substantially rigid projecting teeth formed integrally of the body material around the inner periphery of said open mouth, said teeth extending inwardly and upwardly into said hollow body, spring clamping means compressed in the body exerting an expansion force in the direction of said mouth from a bearing surface on said upper hand grip portion of the body, said spring clamping means extending from said bearing surface and in inoperative position being in compressive engagement against said teeth, said clamping means being actuatable by the entrance of a small amount of material into said mouth to clamp said amount of material against said upwardly projecting teeth, thereby holding said material with the major portion thereof in position for use externally of said hollow body.

2. The invention according to claim 1, said internal spring clamping means comprising a

coil spring extending longitudinally of the body from a seat opposite the mouth of the holder and terminating adjacent said material engaging teeth.

3. The invention according to claim 1, said internal spring clamping means comprising a coil spring disposed longitudinally of the body on a seat opposite the mouth of the holder and carrying a disc adjacent said teeth, said disc being actuated by said spring to clamp that portion of the material inserted into the mouth from outside the holder.

4. The invention according to claim 1, said internal spring clamping means comprising an S-shaped spring disposed in the holder and carrying a flat disc adjacent said teeth, said disc being actuated by said spring to clamp that portion of the material inserted into the mouth from outside the holder against said teeth.

5. The invention according to claim 1, said internal spring clamping means comprising a U-shaped spring disposed in the holder and carrying a flat disc adjacent said teeth, said disc being actuated by said spring to clamp that portion of the material inserted into the mouth from outside the holder against said teeth.
